UNITED STATES PATENT OFFICE.

WALTER CLARK DEAN, OF QUITMAN, GEORGIA, ASSIGNOR TO JAMES H. MATHIS AND DUNHAM B. PRICE, OF QUITMAN, GEORGIA.

INTERCHANGEABLE TELEGRAPHIC KEY.

SPECIFICATION forming part of Letters Patent No. 770,628, dated September 20, 1904.

Application filed November 30, 1903. Serial No. 183,309. (No model.)

To all whom it may concern:

Be it known that I, WALTER CLARK DEAN, a citizen of the United States, residing at Quitman, in the county of Brooks and State 5 of Georgia, have invented a new and useful Improvement in Interchangeable Telegraphic Keys, of which the following is a specification.

My invention is an improvement upon that 10 form of interchangeable telegraphic key or combined key and switch in which a single key is so constructed and arranged as to be used in common with any number of telegraphic circuits and instruments, doing away 15 with the necessity for a separate key for each instrument, economizing board-space, and avoiding the necessity of the operator changing his position from one instrument to another and also of carrying a type-writer from 20 instrument to instrument when messages are to be transcribed thereon.

The invention consists in the novel construction and arrangement of the key, its mounting, switches, and contacts, as will be 25 hereinafter fully described with reference to the drawings, in which—

Figure 1 is a top plan view; Fig. 2, an inverted plan view; Fig. 3, a vertical section on line 3 3 of Fig. 1, and Fig. 4 is a section on 30 the curved line 4 4 of Fig. 2.

In the drawings, A represents a suitable base provided with screw-holes at the corners to enable it to be attached to the board or table, and B is an ordinary telegraphic key. 35 On top of the base A is a non-conducting circular disk D. Upon this disk are mounted metallic contact-plates a b c on one side and a' b' c' on the other. The pair of contacts a a' belong to one circuit, b b' to another circuit, 40 and c c' to still another circuit. As shown, there are three pairs of these contacts, which represent three different circuits of three different telegraphic instruments. There may, however, be any number of circuits and any 45 number of pairs of contacts as may be desired.

The telegraphic key B is mounted upon a swiveling turn-table C, which by a central bolt C' is secured to the base A. On one side of the turn-table (see Fig. 3) a flat spring B³

is secured between the body C of the turn-table and an upper non-conducting disk C², and this spring is by means of a screw s in electrical contact with the metal body B' of the key. The spring B³ plays over and comes into rubbing contact with any one of the three contact-plates a b c as the turn-table is rotated. On the opposite side of the turn-table there is another flat spring B², which rubs upon any one of the contact-plates a' b' c'. This spring is by means of screw e² in electrical contact with the anvil pin or point e', which latter is insulated from the other metal parts of the key by a non-conducting bushing i and the non-conducting disk C².

The key-lever B is normally held up by a spring, as usual, so that ordinarily the two platinum points e and e' are out of contact and the circuit is broken between the plates b and b'; but when the key B is depressed and points e and e' are in contact then the current flows 65 from contact-plate b to plate b' through the following path: from plate b to spring B³, metal frame B' of the key to point e, thence to e', to screw e², to spring B², and plate b'. Plates b and b' are connected, respectively, to circuit-wires b⁶ and b⁷, which lead to a sounder and telegraphic instrument on a definite circuit. In order to compel the current to traverse this path through the key or to pass on direct 70 without going through the key, there is under the base of the instrument (see Fig. 2) a short circuit consisting of a wire b⁵ and switch b⁴. The wire b⁵ is attached to the screw b² and plate b, and the switch b⁴ is adapted to be 75 swung under or away from a clip on screw b³, connecting with plate b'. When the switch b⁴ is out of contact with the clip on screw b³, as shown in Fig. 2, the circuit over wires b⁶ b⁷ may be made through the key-points e e'; but when the switch b⁴ is in contact with the clip 80 of screw b³ the circuit over the wires b⁶ b⁷ is short-circuited under the base of the instrument through wire b⁵ and is not opened by the key at all, but is continuously closed independent of the operation of the key. The action of the key in relation to the contact-plates b and b' is similar in relation to each of the other pairs of contacts a and a', c and c', and 85 90 95

as many other pairs of contact-plates as it may be desired to use. To bring any other pair of contact-plates into operative relation to the key, it is only necessary to swing the turn-table and key around, so that its springs $B^2 B^3$ shall rest upon another pair of contact-plates and to open the switch a^4 or c^4 under the base, the other switches being closed to maintain the continuity of all other circuits.

- 10 As shown, there are three circuits provided for, the terminals of which are shown at $a^6 a^7$, $b^6 b^7$, and $c^6 c^7$, and each has similar contact-plates, switches, and short circuits and with all of which the single key B and its attached parts are interchangeably used. It will be seen also that any number of circuits may be provided for by simply increasing the pairs of contact-plates on the disk D and their attachments under the base.
- 15 By means of my invention individual keys for each telegraphic instrument are dispensed with, space on the table or board is economized, the operator is not required to move from his position in operating in different circuits, and when the messages are to be transcribed on a type-writer this heavy machine does not have to be carried about from place to place.
- 20 Having thus described my invention, what I claim as new, and desire to secure by Letters Patent, is—

- 30 1. An interchangeable telegraphic key, comprising a base having on its upper face two series of circularly-arranged and insulated contact-faces said two series being disposed on opposite sides of the center, a turn-table pivotally mounted between them to rotate in a horizontal plane and carrying a telegraphic key, a spring contact-plate mounted on one

40 side of the turn-table and in permanent electrical connection with the key and adapted to bear upon any one of the circular series of contacts on one side, another spring contact-plate mounted on the opposite side of the turn-table and in electrical connection with the insulated anvil-pin of the key and adapted to bear upon any one of the circular series of contacts on that side, short circuits for connecting the two series of contact in pairs and means for opening the short circuit of any 45 one of the pairs substantially as and for the purpose described.

2. An interchangeable telegraphic key, comprising a base having on its upper face two series of circularly-arranged and insulated contact-faces, said two series being disposed on opposite sides of the center, a turn-table pivotally mounted between them to rotate in a horizontal plane and carrying a telegraphic key, a spring contact-plate mounted on one 50 side of the turn-table and in permanent electrical connection with the key and adapted to bear upon any one of the circular series of contacts on one side, another spring contact-plate mounted on the opposite side of the turn-table and in electrical connection with the insulated anvil-pin of the key and adapted to bear upon any one of the circular series of contacts on that side, short circuit-wires each 55 having an individual switch arranged beneath the base and connecting in pairs the two series of contacts substantially as and for the purpose described.

70 WALTER CLARK DEAN.
